HEATERS OR THE LIKE FOR BURNING SOLID FUEL

Elmer R. Kaiser and James R. Garvey, Columbus, Ohio, assignors to Bituminous Coal Research, Inc., a corporation of Delaware

Application January 31, 1952, Serial No. 269,217

2 Claims. (Cl. 126—74)

This invention relates to a heater or the like for burning solid fuel such as bituminous coals. More particularly, it pertains to heaters, stoves, boilers and furnaces to be used in residences and small buildings.

The invention provides new apparatus for satisfactorily burning bituminous coals while providing against uneven burning and the escape of fumes or smoke particularly when fresh fuel is fed to the apparatus. At the same time there is new provision made in this invention for incorporating overfire air and an arch, usually of refractory material, which makes novel provision for the avoidance of breakage. At the same time, means are provided when the new heater or the like is closed to seal at least one of the doors to prevent the escape of fumes, gases and smoke aforesaid. In a modification, the opening of a firing door also simultaneously operates the fumes, gases and smoke vent means. The new construction of this invention can readily also be made up as a round heater, stove, boiler or furnace to reduce the space occupied thereby and increase its attractiveness. These various features have long been desired particularly in connection with such apparatus capable of burning solid fuels such as bituminous coals, with their varying degrees of agglomerative and coking properties without loss of combustion, in a manually operated device such as those used in many homes and small buildings.

Other objects and advantages will be apparent from the following description and from the drawings, which are illustrative only, in which:

Figure 1 is a view in front elevation of a heater in the form of a manually operated furnace for a home or small building, which furnace embodies one construction of this invention;

Figure 2 is a view in side elevation of the structure shown in Figure 1, said view being partly in section taken along line II—II of Figure 1;

Figure 3 is a view in section taken along line III—III of Figure 2;

Figure 4 is a detailed view of an overfire air manifold used in the embodiment of Figures 1 and 2, said view of Figure 4 being taken generally along the line IV—IV of Figure 2 with the firing door assembly removed;

Figure 5 is a view of the construction shown in Figure 4 taken generally along line V—V of Figure 4;

Figure 6 is a detailed view in front elevation of the arch construction in the embodiment shown in Figures 1 and 2;

Figure 7 is an enlarged detailed view in front elevation of the firing door of the new structure shown in Figure 1;

Figure 8 is a view in section taken along line VIII—VIII of Figure 7;

Figure 9 is an enlarged detailed view and partly in section of a side elevation showing a fume and smoke vent sub-assembly in the embodiment illustrated in Figures 1 and 2;

Figure 10 is a view in perspective of the sub-assembly shown in Figure 9 in partly open position;

2

Figure 11 is a view, similar to the view shown in Figure 2, of a modified construction of this invention;

Figure 12 is a view in front elevation of a modified firing door and fume and smoke vent sub-assembly construction;

Figure 13 is a view in section taken along line XIII—XIII of Figure 12;

Figure 14 is a plan view of the firing door and fume and smoke vent operator; and

Figure 15 is a view taken along line XV—XV of Figure 14.

Referring to the drawings, a furnace 10 embodying a new construction of this invention may comprise an ornamental base 11 on which a cylindrical metal shell 12 is placed and to which it is secured by bolting or other means. As desired shell 12 may be in ring sections with horizontal joints or in cylindrical sections with generally vertical joints to be connected, again, by bolting or other suitable means. A dome head 13 may be provided having a circular lower edge which is offset to enable head 13 to be seated firmly upon the top edge of shell 12. Head 13 is also provided with an integral or detachable collar 14 to define an opening to a suitable stove pipe or stack for the exhausting of combustion and other gases. The lower end of shell 12 defines an ashpit 15 in the front side of which there is an opening 16 to which a frame 17 is bolted, suitable sealing gaskets being used if desired. Frame 17 is provided with hinge brackets 18. An ashpit door 19 has ears 20, the ears 20 and brackets 18 being in line and drilled for the reception of a hinge pin 21. A handle 22 enables door 19 to be opened and closed. A damper plate 23 is pivotally connected at the top thereof to the face of door 19. In its closed position, damper 23 completely covers an opening 24 in door 19. By swinging damper plate 23 about its pivot all or any part of opening 24 may be uncovered to regulate the admission of primary combustion air to ashpit 15. Primary combustion air enters ashpit 15 through the opening 24 in the quantity regulated by the respective overlapping of said opening by damper 23 and the draft through collar 14, among other factors. It will be evident that the opening or openings for such primary combustion air may be located and extend through shell 12 within the height of ashpit 15 at some location other than such openings being mounted on door 19.

A conventional grate 27 is fastened to shell 12 by any suitable means and defines the top of the ash pit chamber 15. The particular grate 27 shown is a conventional drop center grate having a fixed annular ring 28 which is the portion fixed to shell 12. The central opening at the bottom of ring 28 is closed by the grate plates 29 and 30, lugs 31 holding grate plate 29 to ring 28 and lugs 32 holding grate plate 30 to plate 29, suitable ash sifting and passage openings are provided in the respective parts of grate 27. A handle 33 extends into opening 16 so that the plates 29 and 30 can be rotated in their planes to shake down the fire. The rotation of plate 30 comes up against stops on the upper plate 29 so as to rotate that plate also, there being a lost-motion action between the respective plates as will be well understood. Other conventional forms of grate may also be used.

Shell 12 above ring 28 is lined with refractory wall sections 34, there being vertical joints provided between the respective arcuate sections required to line shell 12. These arcuate refractory sections will be of different heights. Thus, sections 34a will be slightly higher than sections 34b but will not be as high as the sections 34c. The lower ends of the refractory sections may be firmly supported on the annular flange of ring 28 as shown in Figure 2 and, if desired, the radially extended joints between the refractory sections may be cemented with asbestos cement when the furnace 10 is

assembled. The refractory lining sections 34c are set back adjacent their lower ends at the level 35 to provide a recess between the forward edges of those sections above level 35 and the rear vertical surfaces of sections 34a into which a refractory arch 36 may be slidably inserted and supported.

Arch 36 may be made in two or more parts 37 and 38, the adjoining surfaces of the respective parts 37 and 38 having a spaced or undercut portion relative to one another to provide a slot or gap 39. Slot 39 is usually far enough above grate 27 to be out of the zone of active combustion. The respective parts 37 and 38 may directly engage one another at the ends 40. In order to provide uniform loading of the lower brick 38, asbestos or cardboard filler may be inserted in slot 39 during the assembling of the new device thereby evening out the usually uneven surfaces of the fired refractory brick such as the parts 37 and 38 comprise. Such uniform loading prevents undue stressing of the respective parts of the arch 36 particularly in the course of the use of the new device. And, arch part 38 which is subjected to the severest conditions has relative freedom to expand and contract relative to part 37. Similarly, there is sufficient clearance in the arch supporting wall recesses in wall 34c above level 35 to avoid spalling of the refractory due to expansion and contraction forces obtaining in the course of operation. On the other hand, if part 38 in the course of use should burn out or warp, in general it will only be necessary to lift out and replace part 38 and not to replace the entire arch 36. Moreover, as shown in Figures 5 and 6, rectilinear blocks may be employed for arch 36 rather than requiring fabrication of special refractory shapes.

The bottom surface of arch 36 which is at level 35 defines with the vertical walls immediately below level 35 and with grate 27 a combustion gases outlet 41 through which the combustion gases flow before entering an upwardly extending segmental passage 42 between the rear surface of arch 36 and the insides of the refractory wall members 34c. The wall members 34c may be provided with one or more openings or ports 43 which also extend through those portions of shell 12 in alignment therewith to serve as secondary air ports to complete the combustion of any incompletely burned material in the gases passing beneath the arch 36. The gases continuing upwardly through passage 42 strike a baffle 44 fastened to the inside of head 13.

Baffle 44 directs such gases forwardly so as to bring them into contact with the entire interior of head 13, which is usually not insulated. Thereby, the transference of heat to the radiating surface comprising the wall of head 13 is correspondingly increased. Thereafter, the gases pass out through collar 14 and into the stack or stove pipe connected thereto leading to such a stack. A combustion chamber 45 exists in and may be defined by the front surface of arch 36 and the insides of the refractory walls 34a and 34b. The lower portion of that combustion chamber extending from grate 27 to a position above level 35 will usually constitute the zone of active combustion, whereas the upper portion of the combustion chamber 45 will constitute a storage or magazine space for unburned and possibly unignited fuels such as the bituminous coal depicted in Figure 2.

A duct 46 may be provided and attached to the front of shell 12. Duct 46 is open only at the bottom and is provided with a butterfly damper valve 47 therein controlled by a knob 48 to regulate the amount of air permitted to flow through duct 46. A slot or port 49 extends through shell 12 adjacent the upper end of duct 46 so as to place the interior of that duct in communication with the interior of furnace 10. Air entering furnace 10 through duct 46 and slot 49 may be termed overfire air. It passes into the interior of the central section 50 of a manifold. Manifold 50 is fastened to the upper end of shell 12 by any suitable means and

forms therewith a generally inverted L-shape. The inner wall 51 of that L-shape slightly overlaps the top edge of refractory wall section 34b. Holes 52 in horizontally spaced arrangement extend through wall 51 to distribute overfire air in arcuate arrangement in a downward direction into chamber 45 to help to maintain uniform and stable conditions therein.

Similarly, wing sections 53 of such a manifold are fastened to the upper end of shell 12 and form a partly stepped-up arcuate continuation of manifold 50 between the ends thereof and the arch 36. The manifold sections 53 have a downwardly extending wall 54 inwardly spaced from shell 12 and overlapping the top edges of the inner surfaces of the refractory wall sections 34a. If desired, plates may be used to close the ends of the manifold sections 53 next to manifold 50 in that portion of those ends above the top of manifold 50. The vertical overlap between the interior of manifold 50 and the interiors of the wing manifolds 53 causes some of the air entering slot 49 to flow into the sections 53 and out of holes 55 in walls 54. Thereby, the annular distribution downwardly into chamber 45 of overfire air is caused to occur around entire periphery above the tops of the walls 34a and 34b. Such overfire air assists in keeping the fuel in the upper part at least of chamber 45 from becoming ignited or agglomerating to an undesirable extent and also provides an available supply of oxygen.

The front of head 13 is provided with an opening 56 the side edges of which are in registry with an opening 57 in the front of the upper part of shell 12. Openings 56 and 57 define a doorway which is adapted to be closed by a firing door 58. A sealing frame 59 is bolted or otherwise secured in position around the edges of doorway 56-57 respectively to shell 12 and head 13. Frame 59 is provided with a continuous annular outer edge 60 and continuous inner annular edge 61. Thus, flanges 60 and 61 define the inner portion of a sealing recess 62, which portion 62 opens into the interior of head 43 through an opening 63. Firing door 58 is provided with ears 64 which overlap lugs 65 integral with frame 59. An opening is provided in registry through the ears 64 and lugs 65 through the insertion therethrough of hinge pin 66, the respective angle of which may be so set as to normally cause door 58 to swing closed under the influence of gravity. Door 58 is provided with a continuous outer edge 67 extending toward flange 60 for mating engagement therewith when door 58 is closed, the respective flanges 67 and 60 being in contact around the entire periphery of doorway 56-57. Similarly, a continuous inner flange 68 integral with door 58 extends toward flange 61 for mating engagement therewith when door 58 is closed. Thereby, a recess 69 defined by the flange 67 and 68 completes, with recess 62 the entire sealing recess. As a consequence, during operation when door 58 is closed, any gases or fumes which may pass outwardly through doorway 56-57, must pass into sealing recess 62-69 and since that recess is at a pressure slightly less than atmospheric because of the open communication therewith through opening 63 with combustion gases chamber 70. All such gases or fumes will be drawn into chamber 70 which normally is at lower pressure and pass out through collar 14 to the stack or chimney. The seal between door 58 and frame 59 around the mating edges of flanges 61 and 68 is sufficiently tight to prevent any undue disturbance of the flow of overfire air through the manifolds 50 and 53 downwardly into combustion chamber 45. A handle 71 is normally used to open and close door 58. If desired, door 58 may also be provided with a latch ear to coact with a latch strike on frame 59.

Chamber 70 is sealed off from combustion chamber 45 and doorway 56-57 by a partition 72 extending from the top of arch block 37 to the interior of head 13 to the top of the aforesaid doorway thereby forming a differential pressure chamber with respect to the combus-

tion chamber 45. Partition 72 is bolted or otherwise suitably fastened to head 13 and the joints between partition 72 and any other parts such as frame 59 and block 37 may be suitably sealed as by means of a furnace cement. Partition 72 is provided with a vent 73 forming a passage at selected times for the exhausting of gases, fumes and/or smoke from the top of combustion chamber 45 into chamber 70. Around vent opening 73 partition 72 is provided with a continuous upstanding integral flange 74 forming a seat for a vent closure 75, as more clearly shown in Figure 9. Forwardly extending ears 76 coat with lugs 77 fastened to partition 72 by means of a pivot pin 78 passing through aligned openings in the adjacent pairs of ears 76 and lugs 77. An arm 79 is welded or otherwise fastened to closure 75 for engagement by a bent link 80 which extends through an opening 81 in arm 79 above the axis of the pivot pin 78. As will be evident from Figure 9, the rearwardly extending portion of link 80 passes through an opening in the flange of frame 59 and a registering opening in head 13 into chamber 70 to a position where it can pass through opening 81 as aforesaid. A nut 82 may be screwed on the inner end of link 80 to prevent any accidental disassembling of the parts. The outer end of link 80 is bent into the form of a hook 83 which passes around a headed stud 84 fastened upright in the upper ear 64 of door 58. Hence, as the opening of door 58 is begun, stud 84 pulls on link 80 to begin the opening of closure 75 thereby directly exhausting to chamber 70 the space inside furnace 10 adjacent doorway 56-57, causing all gases flowing in that vicinity to pass through chamber 70 in vent 73. When door 58 is closed, the weight of closure 75 seats it relatively tightly on flange 70 closing vent 73. Sufficient clearance spaces between the various elements of the linkage are provided to take care of the respective movements of the parts involved without deflection of them as, for example, where link 80 passes through furnace shell 12 and frame 59. The provision of a head on stud 84 avoids any likelihood of hook 83 becoming disconnected from part 84.

Head 13 and shell 12 as shown in Figure 1 are respectively provided with guide brackets 85 through which a rod 86 slidably extends. The upper end of rod 86 is in the form of a spatula 87 closely adjacent to and beneath that portion of link 80 which is outside of furnace 10 as shown in Figures 9 and 10. In its lower position, end 87 is just out of contact with link 80, or, in any event does not lift link 80 so as to unseat closure 75. The lower end of rod 86 is bent at right angles forming an end 88 which passes through an eye 89 of a crank 90. Crank 90 is held in bearings 91 bolted to base 11. The other end of crank 90 is provided with a foot pedal 92. Hence, by stepping on pedal 92 eye 89 is raised raising rod 86 and end 87 and thus pushing link 80 upwardly, the hook 83 pivoting under the head of stud 84 to open closure 75 as shown in Figure 10. A split set collar 93a is provided on rod 86 at an approximate height so that when the pressure is removed from pedal 92 the weight of the rod 86 will cause it to fall out of engagement with link 80, rod 86 coming to rest when collar 93a butts against upper bracket 85. Normally, pressure will be removed from pedal 92 only after door 58 has been opened, which opening will take over the maintenance of vent 73 in open condition by holding closure 75 up away from flange 74 through arm 79, link 80 and stud 84. When door 58 is then closed, closure 75 will close and seat itself on flange 74 since the operator's foot has theretofore usually been removed from pedal 92. The advantage of pedal 92 and rod 86 sub-assembly is that vent 73 can be opened, if desired, in advance of firing door 58 thereby further insuring against any discharge of gases, fumes, vapors or smoke from combustion chamber 45 into the room or space in which furnace 10 is located.

6

A modification of the new construction of this invention is illustrated in Figure 11. The parts thereof generally corresponding in construction and functioning are correspondingly numbered with the addition of a prime accent thereto. In supplying combustion air, a duct 46' is utilized in cooperation with a port 94 intermediate ring 28' and port 49'. An adjustable butterfly valve 93 is interposed in the lower part of duct 46' and may be used to adjust all air entering duct 46' including such combustion air. The primary combustion air entering port 94 passes downwardly through a slot 95, which is arcuate in plan, in wall section 34b'. An arcuate slot 96 in ring 28' permits such primary combustion air to pass into ashpit 15' and upwardly through grate 27' into the active combustion zone of the fire adjacent that grate. Thereby, the primary combustion air is preheated by convection against the surfaces of slot 95. Normally, the modification shown in Figure 11 would be used with furnaces or boilers of larger capacity in terms of heat output where such larger capacity is required.

The remainder of the air passing through port 94 in shell 12' acts somewhat in the nature of crossfire air and proceeds through an inwardly directed opening 97 passing entirely through wall 34b'. Such crossfire air enters combustion chamber 45' adjacent the top of the active combustion zone and may assist in attaining relatively higher rates of burning than those attainable by the use of the embodiment illustrated in Figure 2.

A modified firing door and smoke and fume subassembly made in accordance with the teaching of this invention is illustrated in Figures 12 to 15, inclusive and may be used in connection with the structures shown in Figures 2 and 11 in lieu of the particular construction illustrated therewith. In the modified sub-assembly, a firing door 100 is provided and conventionally hinged to a frame 101 corresponding in general construction and functioning to door 58 and frame 59, respectively. Thus, an annular sealing recess or channel 102 is in connection with a heating and flue chamber 70" through an opening 103 respectively through frame 101, and head 13". A partition 72" is also provided similar in general construction and functioning to partition 72. In the doorway defined by the opening through frame 101 a smoke curtain 104 in the form of a hanging plate may be provided. Pivot 105 pass through lugs 106 and adjacent ears 107 respectively on frame 101 and plate 104. The fit between swingable hanging plate 104 and opening 101a is sufficiently close to act as a baffle or barrier for the upper part of opening 101a. Hence, if there should be any tendency when door 100 is opened for fumes, gases or smoke to issue through opening 101a, they will be impeded by plate 104 and generally directed inwardly again facilitating their removal through a vent 73" in partition 72".

The lower part of frame 101 is provided with lugs 108 adjacent ears 109. Ears 109 are integral with a chute 110, pivot pins 111 joining chute 110 swingably to frame 101. The width of chute 110 is also sufficient to fill up when in the position shown in Figure 13 substantially the entire remainder of opening 101a when taken in conjunction with curtain 104. Thus, in the position shown in Figure 13 curtain 104 and chute 110 shield the inner surface of door 100 and thereby materially minimize the deposit thereon of soot or other layer of impalpable solids which might catch fire outside of furnace 10 when door 100 is opened. When door 100 is opened, chute 110 under the influence of gravity falls into the position illustrated by the reference numeral 110a as shown in dot and dash lines in Figure 13. Thereby, it facilitates the charging of combustion chamber 45" with solid fuel and shields the lower edge of opening 101a whereby door 100 may be readily closed after the fuel-charging operation. When door 100 is opened, curtain 104 remains generally in the position

shown in Figure 13 but if for any reason the full opening 101a is required curtain 104 can be raised by swinging the lower end thereof outwardly through opening 101a. On each side of frame 101 there is a stop 101b integral therewith which prevents curtain 104 from swinging inwardly of the position shown in Figure 13. The upper end 110b of chute 110 is so constructed that in the position shown in full lines of Figure 13 with door 100 closed, such end rests against the lower end of curtain 104 to complete the shielding aforesaid of the inside of door 100. The raising of chute 110 into the position shown in full lines in Figure 13 is performed by the act of closing door 100. As door 100 is swung into closed position a cam 112 engages the exterior of the curved end 110b swinging chute 110 upwardly from the position 110a into its position 110 shown in solid lines in Figure 13. Integral brackets 110c on the outer side chute 110 limit the outwardly and downwardly movement of chute 110 to cause it to rest in the position shown in dot and dash lines 110a in Figure 13.

Door 100 is provided with an integral latch wedge 113 for engagement by a registering wedge surface 114 the latter of which is integral with a handle 115 pivoted at 116 to shell 13". Handle 115 is provided with an integral extension 117 to operate a crank 118 through a link 119 pivoted respectively to arm 117 and crank 118. Shaft 120 of crank 118 extends through shell 13" and is supported in a tubular bearing 121. The inner end 122 of crank 118 is pivoted and provided with an eye through which the upper link of a chain 123 is fastened. The lower end of chain 123 passes through the upstanding extension of arm 79". Arm 79" is fastened or otherwise secured to closure 75". Hence, the act of unlatching door 100 by raising handle 115 in the direction of arrow shown in Figure 12 also and simultaneously raises closure 75" into the position shown in dot and dash lines in Figure 15 to vent any gases, fumes and/or smoke which might tend to drift through opening 101a as door 100 is being opened or while it is open.

Although the foregoing embodiments of this invention are illustrated in connection with a gas-to-gas type of heat transfer, it is evident that the walls of the embodiment shown may in part or substantially entirely be composed of water cooled sections, for example, for the generation of steam or the heating of water for a hot water heating system. Moreover, particularly the upper part of the new arch construction of this invention may be a water cooled or boiler section for gas-to-liquid heat transfer. In addition, the combustion gases may be led to other types of heating transfer surfaces, a particular advantage of the embodiment shown being that they can be constructed in the form of very compact round or rectilinear heaters of attractive appearance for residential and other relatively low-duty uses.

This invention may be variously practiced without departing from the spirit thereof as defined in the appended claims.

We claim:

1. In a heater or the like for burning solid fuel, in combination, a round shell, a combustion chamber inside said shell, a combustion gases passage inside said shell, said passage being defined by a refractory arch associated with said shell, a gas outlet beneath the bottom of said arch connecting said chamber and said passage, a duct on the outside of said shell, a port through said shell communicating with the interior of said duct and supplying overfire air, a manifold extending around the top of said combustion chamber, the interior of said manifold being in communication with said port, annularly spaced open-

ings between the interior of said manifold and said combustion chamber, a grate adjacent the bottom of said combustion chamber, a firing door adjacent said manifold, spaced flanges on said firing door extending toward said heater to provide a sealing recess, a combustion gases dome above said passage to define a combustion gases chamber in communication with said sealing recess, a partition between said last-mentioned chamber and said combustion chamber, a fume vent assembly in said partition, linkage means for placing said combustion chamber in communication with said combustion gases chamber before said firing door is opened, and linkage means between said firing door and said assembly to at least hold said fume vent assembly in open position while said firing door is open.

2. In a heater or the like for burning solid fuel, in combination, a round shell, a combustion chamber inside said shell, a combustion gases passage inside said shell, said passage being defined by a removable partible planar refractory arch associated with said shell, a gas outlet beneath the bottom of said arch connecting said chamber and said passage, a duct on the outside of said shell, a port through said shell communicating with the interior of said duct to supply overfire air, a manifold extending around the top of said combustion chamber, the interior of said manifold being in communication with said port, annularly spaced openings between the interior of said manifold and said combustion chamber, a grate adjacent the bottom of said combustion chamber, means for supplying primary combustion air through said grate, means for supplying secondary air adjacent the bottom of said arch, a normally closed firing door adjacent said manifold, spaced flanges on said firing door extending toward said heater to provide a sealing recess, a combustion gases dome above said passage to define a combustion gases chamber in communication with said sealing recess, a partition between said last-mentioned chamber and said combustion chamber, and means for placing said combustion chamber in communication with said combustion gases chamber when said firing door is open.
